UNITED STATES PATENT OFFICE.

OLIVER S. LYFORD, JR., OF CHICAGO, ILLINOIS, ASSIGNOR TO THE SIEMENS & HALSKE ELECTRIC COMPANY OF AMERICA, OF SAME PLACE.

ELECTRIC-ARC LAMP.

SPECIFICATION forming part of Letters Patent No. 562,313, dated June 16, 1896.

Application filed April 6, 1896. Serial No. 586,287. (No model.)

To all whom it may concern:

Be it known that I, OLIVER S. LYFORD, Jr., a citizen of the United States, residing at Chicago, in the county of Cook and State of Illinois, have invented a certain new and useful Improvement in Arc-Lamps, (Case No. 90,) of which the following is a full, clear, concise, and exact description, reference being had to the accompanying drawings, forming a part 10 of this specification.

My invention relates to an improvement in arc-lamps, the object thereof being to provide means for arresting the combustion of the lamp-carbons, while avoiding the disadvantages attendant upon maintaining the arc in a more or less complete vacuum.

Arc-lamps have hitherto been constructed with this end in view, wherein the arc was maintained in a globe normally sealed from 20 the external air, but provided with valves designed to equalize differences of pressure upon the exterior and interior of said globe. As it is not necessary to maintain the arc in a vacuum in order to secure practically the 25 same results as to lengthening the life of lamp-carbons and like desirable results can be obtained by permitting sufficient communication between the interior and the exterior of the arc-chamber to allow at all times the 30 equalization of pressure, I have provided for the arc-chamber a port which is sealed by a porous or fibrous diaphragm adapted to permit the entrance of air or the exit of gases when the pressure upon the interior and exterior are unequal, and which practically seals 35 the said chamber from the external air at all other times.

The device of the present application will be more readily understood by reference to 40 the accompanying drawings, in which—

Figure 1 is a view, partly in section, illustrating a lamp provided with my device. Fig. 2 shows in detail the porous diaphragm closing the port.

Like letters refer to like parts throughout both views.

The arc-lamp *a* of the usual construction is fitted with a globe *b*, of glass or semitransparent material, which completely incloses 50 the arc *c* and lower portion of the frame *d*. To the upper portion of the globe is sealed

the casing *e*, which serves to completely close the arc-chamber *f*, except for the port *g*, preferably situated above the arc in the casing *e*. Port *g* is provided for the equalization of the 55 internal and external pressures upon the globe without permitting the entrance within the globe of sufficient oxygen to materially increase the combustion of the carbons, the said port being closed by a diaphragm *h* of 60 any suitable porous or fibrous material, such as asbestos or felt, through which the air or gases will necessarily have to pass to either enter or leave the arc-chamber. Thus, ordinarily, there will be no appreciable circulation of air through the diaphragm and, the 65 oxygen being excluded from the arc-chamber, the combustion of the carbons will be almost entirely arrested. By thus employing a simpler construction, wherein a diaphragm is provided for equalizing the pressures upon the exterior and interior of the arc-chamber, all 70 difficulties attendant upon the liability of an equalizing-valve to become fast in its seat, remain open, or otherwise fail to respond to 75 variations in pressure, are avoided.

Having thus described my invention, what I claim as new, and desire to secure by Letters Patent, is—

1. In an arc-lamp, the combination with an 80 inclosing chamber for the carbon electrodes normally sealed from the external air, of a porous or fibrous diaphragm for securing the equalization of any substantial difference between the external and internal pressures 85 upon the walls of the said inclosing chamber, substantially as described.

2. In a sealed casing for an electric-arc lamp, the combination with a port connecting the interior thereof with the external air, 90 of a porous or fibrous diaphragm normally closing the said port while permitting the passage of air or gas freely through the said port when influenced by a difference in the external and internal pressures upon said casing, substantially as described.

3. In an arc-lamp, the combination with the arc, of a globe and casing forming an arc-chamber, a port provided in said casing, and a porous or fibrous diaphragm normally sealing the said port, preventing the passage of air or gas, adapted freely to permit their pas- 100

sage to equalize any material differences between the pressure within the interior of the arc-chamber and the atmospheric pressure, substantially as described.

- 5 4. In an arc-lamp, the combination with the globe *b* inclosing the arc, of the casing *e* sealed to the globe and forming with said globe an arc-chamber, port *g* provided in the arc-chamber, and porous or fibrous diaphragm 10 *h* closing said port and normally maintaining the arc-chamber sealed from the external air,

but adapted to permit exit of gases from within or the entrance of air from without as the pressure within the arc-chamber is greater or less than the pressure of the external air, substantially as described. 15

In witness whereof I hereunto subscribe my name this 1st day of April, A. D. 1896.

OLIVER S. LYFORD, JR.
